[57] CLAIM

The ornamental design for a tennis ball container, as shown and described.

DESCRIPTION

FIG. 1 is a perspective view of a tennis ball container showing our new design;
 FIG. 2 is a front elevation of the tennis ball container, the rear and side elevations are the same;
 FIG. 3 is a top view thereof; and,
 FIG. 4 is a bottom view thereof.

The broken lines in FIG. 1 showing tennis balls are for illustrative purpose only and form no part of the claimed design.
